Filed April 12, 1945 4 Sheets-Sheet 2

This diagram illustrates an exploded view of a mechanical assembly, possibly a gun mechanism. The parts are labeled with numbers 16 through 61. Key components include a main body (16), a central rod (37), a lever system (35, 32, 19, 16, 45, 17, 22, 15, 20, 24, 23), and a base assembly (29, 30, 36, 18, 19, 41, 22, 20). The diagram shows how these parts interlock and function together.

Fig. 3.

Fig. 6.

The diagram shows a vertical cylindrical component with a central tube. At the top, there is a circular assembly with a gauge-like structure labeled '16' and a valve or fitting labeled '28'. A handle or lever labeled '32' extends downwards from this assembly. The central tube has a flared bottom labeled '31'. The lower part of the cylinder is labeled '29' and '30'. At the very bottom, there is a square base with a circular hole, labeled '35' and '36'. A small number '26' is also visible near the bottom.

HOIST

Walter O. Ladwig, Milwaukee, Wis., assignor to
 Otto Ladwig & Sons, Inc., Milwaukee, Wis.

Application April 12, 1945, Serial No. 587,952

10 Claims. (Cl. 212—35)

This invention appertains to loading and unloading and more particularly to a novel crane for facilitating the handling of material.

In the manufacture of concrete and similar blocks, much difficulty is experienced in the transferring of green building blocks from the molds to the cars utilized for conveying the blocks into the kilns. Not only is this a laborious and time-consuming job, but where the green blocks are handled by hand, the blocks are often damaged.

It is, therefore, one of the salient objects of my invention to provide a novel hoist or crane which will effectively receive the blocks from the molds and transfer the same to the truck kilns in a rapid manner without danger of injuring the blocks and with the reduction of manual labor.

Another salient object of my invention is to provide a novel hydraulic or air-operated hoist for lifting and placing articles of any type from one point to another, which will be easy to operate and which can be readily manipulated by the ordinary layman.

A further object of my invention is to provide a novel hoist or crane having a swinging boom with an air or similarly operated piston so arranged relative to the boom that the boom can be quickly and conveniently raised and lowered at the will of the operator of the crane.

A further important object of my invention is to provide a load-carrying extension on the boom pivotally connected therewith, in combination with novel means for maintaining said extension parallel to the ground irrespective of the angular position of the boom, whereby danger of accidentally dumping the load is reduced to a minimum.

A still further object of my invention is to provide a hoist or crane which can be readily associated with a column or post and one which will occupy a minimum amount of floor space.

A still further important object of my invention is to provide a hoist or crane of the above character, which will be durable and efficient in use, one that will be simple and easy to manufacture and one which can be placed upon the market and set up for use at a comparatively low cost.

With these and other objects in view the invention consists in the novel construction, arrangement and formation of parts, as will be herein-after more specifically described, claimed and illustrated in the accompanying drawings, in which drawings:

Figure 1 is a side-elevational view of my novel hoist or crane, parts of the view being shown broken away and in section to illustrate structural detail.

Figure 2 is a horizontal sectional view taken substantially on the line 2—2 of Figure 1, looking in the direction of the arrows.

Figure 3 is an enlarged detail fragmentary vertical view taken substantially on the line 3—3 of Figure 1, looking in the direction of the arrows illustrating the novel mechanism employed for raising and lowering the boom.

5 Figure 4 is an enlarged detail horizontal sectional view taken on the line 4—4 of Figure 1, looking in the direction of the arrows, illustrating the connection of the boom with the swinging support.

10 Figure 5 is a sectional view similar to Figure 4, but taken on the line 5—5 of Figure 1, looking in the direction of the arrows, illustrating the connection of the supporting strut or auxiliary boom utilized for keeping the load-carrying extension in a horizontal position at all times.

15 Figure 6 is an enlarged detail vertical sectional view taken on the line 6—6 of Figure 1, looking in the direction of the arrows, showing the load-carrying basket and its connection with the boom extension.

20 Figure 7 is a detail horizontal sectional view taken on the line 7—7 of Figure 1, showing the load-carrying basket.

25 Figure 8 is a detail side elevational view of the basket.

Figure 9 is a side elevational view of a slightly modified form of my novel hoist or crane.

30 Figure 10 is a top plan view of the same.

Figure 11 is an enlarged detail vertical sectional view taken on the line 11—11 of Figure 9, looking in the direction of the arrows, illustrating the novel means employed for raising and lowering the boom.

35 Figure 12 is a detail substantially horizontal sectional view taken on the line 12—12 of Figure 9, looking in the direction of the arrows, illustrating the connection between the boom and its support and the guide for said boom.

40 Figure 13 is a detail fragmentary sectional view taken on the line 13—13 of Figure 9, looking in the direction of the arrows, illustrating a preferred means of connecting my crane with a column or post.

45 Referring to the drawings in detail, wherein similar reference characters designate corresponding parts throughout the several views, the letter "C" generally indicates my novel hoist or crane and the same includes a swinging supporting structure 15 for the boom 16.

50 The supporting structure 15 is in the nature of a bracket and can consist of an upright channel beam 17 of a U shape in cross section, and this beam has formed thereon or secured thereto a

55 horizontally disposed channel beam 18. A reinforcing plate 19 can be employed for bracing the vertical and horizontal beams 17 and 18. In order that the supporting structure 15 can be swung at different angles upper and lower bearing brackets rotatably receive bearing studs 22 car-

ried by the terminals of the vertical beam 17. The bearing brackets 20 and 21 form admirable means for permitting the convenient connection of the supporting structure 15 for swinging movement with a support such as a wall, or the like. As shown in Figures 1 and 2, the bearing brackets can be mounted upon a supporting column 23. U-shaped clamp bolts 24 are employed for connecting these brackets to the column.

In accordance with my invention the flanges of the vertical beam 17 are provided with a plurality of equi-distantly spaced adjustment openings 25 for a purpose, which will be later set forth. The horizontal beam 18 is provided with similar openings 26.

The boom 16 can be made from any desired material, and as illustrated, the same is formed from a length of steel tubing. The inner end of the boom is apertured for the reception of a pivot bolt 27, and this bolt can be placed through any of the openings 25 so as to vary the distance of the boom from the ground. Welded or otherwise secured to the lower face of the boom above the horizontal beam 18 is a rib 27', and this rib is provided with a series of openings 28. Placed between the boom 16 and the horizontally disposed beam 18 is the operating mechanism 29 for raising and lowering the boom. This operating mechanism includes a cylinder 30 having mounted therein for sliding movement a piston 31. Secured to the piston and extending through the upper head of the cylinder is a piston rod 32, and this piston rod terminates in a yoke 33 for embracing the rib 27. A pivot bolt 34 passes through said yoke and through any one of the openings 28. The lower end of the cylinder 30 has formed thereon or secured thereto a depending U-shaped saddle 35 which is adapted to embrace the beam 18. A pivot bolt 36 extends through the saddle and any of the selected openings 26. Obviously, the operating mechanism can be adjusted back and forth so as to vary the position thereof relative to the pivot point of the boom 16 and by varying the position of the operating mechanism, the height of the raising and lowering of the boom can be controlled.

One of the important features of my invention is the provision of a boom extension 37, and this extension is in the nature of a track, for a purpose, which will be later set forth. This track or boom extension 37 is of an inverted U shape in cross section and is provided with inturned flanges or guides 38. The inner end of the boom extension 37 has ears 40 formed thereon which embrace the outer end of the boom 16. A pivoted bolt 41 pivotally connects these ears with the boom.

Mounted for traveling movement along the boom extension is a wheeled trolley or carriage 42, and the wheels thereof travel in said flanges or guides 38. Secured to this carriage for movement therewith is a suspension cable 43, and this cable in turn has connected therewith the device 44 for carrying the load. This device will be later described.

By forcing the piston of the operating mechanism 29 toward the upper end of the cylinder the boom 16 can be raised and by allowing the piston to slide downwardly in the cylinder the boom can be lowered.

Means is provided for maintaining the boom extension in a horizontal plane, and this can be accomplished by the use of an auxiliary boom 45. The forward end of the auxiliary boom 45 is pivotally connected as at 45' to the upper end of

an upstanding bracket 46, welded or otherwise secured to the inner end of the boom extension, and the rear end of the auxiliary boom 45 is pivotally connected to the vertical beam 17 of the supporting structure 15 by a pivot bolt 47. This bolt can be placed in the desired openings 25. A brace rod structure 37' can be utilized for connecting the upper end of the bracket 46 with the outer end of the track or boom extension 37. Obviously, the auxiliary boom 45 is so positioned relative to the main boom 16, that during the raising and lowering of the main boom, the auxiliary boom will swing the boom or track extension 37 on the main boom 16 and maintain said extension in a horizontal plane at all times.

The device 44 for carrying the load can be in the nature of a grapple or the like according to the character of the material being handled. In the present instance, the device 44 has been especially designed for handling building blocks and the same is constructed in the nature of a basket or platform for receiving blocks. Hence, the same includes a transversely extending main bar 48 having sockets 49 therein for receiving the inner ends of supporting fingers 50. As many of these fingers can be used as desired, and the same can be adjusted relative to one another by placing said fingers in different sockets 49. Set screws 51 are threaded into the main bar 48 for binding engagement with the inner ends of the fingers. Secured to the opposite ends of the main bar 48 are upright straps or the like 52, and these straps are in turn secured to a suspension bracket 53. This suspension bracket embodies a top U-shaped frame 54 having formed on its rear ends depending legs 55, and these legs have their lower ends connected by cross brace 56. The cross brace 56 is in turn connected to the main supporting bar 48 by forwardly extending legs 57. The cable 43 is connected to the front central portion of the bracket 53 by means of an eye 55' and a link 56'. The device 44 is so constructed that blocks and the like can be readily slid on the fingers 50, and as the cable will be directly above the block supported by the fingers, the balancing of the basket is assured. It can be seen that the front of the device 44 is open, which allows the convenient sliding of blocks on and off the fingers.

Any preferred means can be utilized for controlling the flow of fluid, such as air under pressure to and from the lower end of the cylinder 30. Connected with the cylinder and communicating with a port formed therein is a length of flexible tubing 58. This tubing 58 is connected by suitable clips 59 with the boom 16 and with the cable 43. The tubing 58 communicates with a substantially U-shaped air conduit pipe 60 which is rigidly secured to the frame 53. Communicating with one end of the pipe 60 is an air feed flexible conduit tube 61 which leads from a suitable source of supply of air under pressure. Arranged in the length of the pipe 60 adjacent to the air feed conduit or tubing 61 is a hand-operated control valve 62. The operator by actuating the lever of the hand valve can control the flow of air under pressure from the source of supply to the cylinder 30 for the raising of the boom. Carried by the opposite end of the pipe 60 is an outlet or bleed valve 63 and by actuating this bleed valve, escape of air from the conduit 60 and the cylinder is permitted. The weight of the boom and the load carried thereby will automatically lower the piston in the cylinder.

From the foregoing description, it can be seen

that not only can the boom with a load be quickly raised and lowered but that also the boom can be swung in an arc of a circle on the vertical pivots 22. Thus the load can be readily moved from one point to another. Likewise, due to the traveling carriage 42 and the formation of the boom extension 37, the basket 44 or grapple as the case may be can be moved longitudinally of the boom. Means can be provided for limiting the swinging of the boom in either direction on the column or post 23 if such should be desired.

In view of the fact that the boom extension 37 will always be maintained in a horizontal plane the accidental movement of the wheeled carriage 42 on the tracks on said extension will be prevented.

In Figures 9 to 13, inclusive, I have shown a slightly modified form of my invention. In this form I also provide a suitable supporting structure 65 which can include upper and lower bearing members 66 and 67 firmly united by brace rods 68. These bearing members can be connected to a pivot shaft 69 which is in turn carried by bearing brackets 70. These bearing brackets can be bolted to a desired support or to a column or post 71 by U-shaped bolts 72. Rigidly connected to the upper bearing 66 is a supporting platform 73 and angle brace rods 74 can be employed for connecting the outer end of the platform with the lower bearing 67.

Mounted upon the platform 73 are two spaced pairs of guide bars 75, and these guide bars can be of an angle iron construction, if so desired. The upper ends of these angle bars 75 can be connected to a head or cap 76 which firmly unites said angle or guide bars 75. Brace bars 77 can be employed for connecting the head 76 with the platform. Guided by the angle bars 75 is a cross head 78, and this cross head has connected thereto the piston rod 79 of the operating piston 80. This piston is mounted for sliding movement in a cylinder 81 which depends from the platform 73. Mounted above the platform 73 is the forwardly extending boom 82, and the boom in this form of my invention can be constructed from a length of I beam. The cross head 78 can include a cross bolt 83 which extends through said boom and the cross bolt can have mounted thereon anti-friction roller sleeves 84. Carried by the ends of the bolt 83 are washers 85. These washers engage the outer faces of the guide or angle bars 75 and the boom 82 is mounted between said pairs of angle or guide bars. Consequently, movement of the boom is effectively guided by said pairs of guide or angle bars 75.

Pivotedly connected to the forward end of the boom 82 is a boom extension 86 and this boom extension can be of the same character as the boom extension 37 shown in the first form of my invention. It is to be also noted that this boom extension carries for traveling movement the load carrying basket 87 which is also of the same construction as the load carrying basket 44.

In accordance with this form of my invention, I rigidly secure to the boom extension 86 an upright frame 88 and the upper end of this frame has pivotally connected thereto, as at 89, the auxiliary parallel boom 90. The auxiliary boom 90 extends rearwardly of the frame 88 and the rear end of this auxiliary boom is connected to the platform 73 by a pair of toggle levers 91 and 92. The toggle lever 91 is connected by pivot pin 93 with the auxiliary boom, while the toggle lever 92 is pivotally connected by pin 94 with a rib 95 secured to the platform 73. This rib is pro-

vided with a series of openings, and the pivot pin 94 can be placed in any selected opening to vary the position of the toggle levers and the boom. It is to be noted that the meeting ends 5 of the toggle levers 91 and 92 are pivotally connected together by a pivot pin 95 and this pivot pin extends through any selected opening of a plurality of openings 96 formed in the inner end of the boom 82. By this arrangement, it can be seen that the boom and the toggle levers can be adjusted to suit varying conditions. A pivot link 97 is employed for connecting the upper end of the toggle lever 91 with a cap 76, and this link 97 is pivotally mounted on the pivot pin 93 and is connected with the cap 76 by pivot pin 98.

In use of this form of my invention, when air is admitted to the lower end of the cylinder 81 the piston 80 will be raised and this will forcibly move the boom 82 to a raised position. In view 20 of the connection of the auxiliary beam 90 with the toggle lever 91 and the upright frame 88 the boom extension 86 will be maintained in a horizontal position. When it is desired to lower the boom, it is merely necessary to release the air from the bottom of the cylinder.

From the foregoing description, it can be seen that I have provided an exceptionally simple and durable form of hoist which can be readily and easily manipulated by a layman without particular skill or training.

While I have shown my hoist or boom as connected to a supporting column in a building, it is to be understood that my crane or hoist can be effectively used on a mobile device, such as a truck.

Changes in details may be made without departing from the spirit or the scope of my invention, but what I claim as new is:

1. A crane comprising a support, a boom pivotally mounted at its inner end on said support, means for swinging the boom on the support to different angular raising and lowering positions, a track boom extension pivotally connected to the outer end of the boom, a load carrier slidably mounted in said track boom extension, and means for maintaining said track boom extension in a horizontal plane at all times during the raising and lowering movement of the boom.

2. A crane comprising a support, a boom rockably mounted at its inner end and upon the support for swinging movement in a vertical plane to a raised and lowered position, a boom extension pivotally connected to the outer end of the boom, a load carrier slidably mounted upon the boom extension, means for raising and lowering the boom, and an auxiliary boom structure pivotally connecting the boom extension with the support for maintaining said boom extension in a horizontal plane at all times during the swinging movement of the boom.

3. A crane comprising a support, a boom rockably mounted at its inner end upon the support for swinging movement in a vertical plane to a raised and lowered position, a boom extension pivotally connected to the outer end of the boom, a load carrier slidably mounted upon the boom extension, means for raising and lowering the boom, and an auxiliary boom structure pivotally connecting the boom extension with the support for maintaining said boom extension in a horizontal plane at all times during the swinging movement of the boom, and means including a vertical pivot operatively connected with said support, whereby the support and boom can be swung together in a horizontal plane.

4. A crane comprising a support including a vertical leg and a horizontal leg, bearing brackets rotatably connected with the support whereby the support can be swung in a horizontal plane, means securing the brackets to a rigid member, a boom rockably connected at its inner end to the vertical leg, a track boom extension pivotally connected to the outer end of the boom, a carriage slidably mounted in said track boom extension, a load carrier secured to said carriage, a cylinder pivotally secured to the horizontal leg of the support, a piston slidably mounted in the cylinder, a piston rod secured to the piston extending exteriorly of the cylinder and pivotally connected to said boom forwardly of the vertical leg, means on said load carrier for controlling the flow of fluid to and from the cylinder, and an auxiliary boom having pivotal connection with the track boom extension and to the vertical leg.

5. A crane comprising a support including a vertical leg and a horizontal leg, bearing brackets rotatably connected with the support whereby the support can be swung in a horizontal plane, means securing the brackets to a rigid member, a boom rockably connected at its inner end to the vertical leg, a track boom extension pivotally connected to the outer end of the boom, a carriage slidably mounted in said track boom extension, a load carrier secured to said carriage, a cylinder pivotally secured to the horizontal leg of the support, a piston slidably mounted in the cylinder, a piston rod secured to the piston extending exteriorly of the cylinder and pivotally connected to said boom forwardly of the vertical leg, means on said load carrier for controlling the flow of fluid to and from the cylinder, an auxiliary boom pivotally connected with the track boom extension and to the vertical leg, and means for varying the position of the boom and the auxiliary boom on the vertical leg.

6. A crane comprising a support including a vertical leg and a horizontal leg, bearing brackets rotatably connected with the support whereby the support can be swung in a horizontal plane, means securing the brackets to a rigid member, a boom rockably connected at its inner end to the vertical leg, a track boom extension pivotally connected to the outer end of the boom, a carriage slidably mounted in said track boom extension, a load carrier secured to said carriage, a cylinder pivotally secured to the horizontal leg of the support, a piston slidably mounted in the cylinder, a piston rod secured to the piston extending exteriorly of the cylinder and pivotally connected to said boom forwardly of the vertical leg, means on said load carrier for controlling the flow of fluid to and from the cylinder, an auxiliary boom pivotally connected with the track boom extension and to the vertical leg, and means for varying the position of the cylinder and piston rod relative to the boom and to the horizontal leg of the support.

7. A crane comprising a support including a vertical leg and a horizontal leg, bearing brackets rotatably connected with the support whereby the support can be swung in a horizontal plane, means securing the brackets to a rigid member, a main boom rockably connected at its inner end to the vertical leg, a track boom extension pivotally connected to the outer end of the main boom, a carriage slidably mounted in said track boom extension, a load carrier secured to said carriage, a cylinder pivotally secured to the horizontal leg of the support, a piston slidably mounted in the cylinder, a piston rod secured to the piston extending exteriorly of the cylinder

and pivotally connected to said main boom forwardly of the vertical leg, means on said load carrier for controlling the flow of fluid to and from the cylinder, an auxiliary boom pivotally connected with the track boom extension and to the vertical leg, means for varying the position of the main boom and auxiliary boom in the vertical leg of the support, and means for varying the position of the cylinder and piston rod relative to the horizontal leg of the main boom.

8. A crane comprising a support, including a vertical leg and a horizontal leg, bearing brackets, means securing the bearing brackets to a rigid member, means rotatably connecting the support with the bearing brackets for swinging movement in a horizontal plane, a main boom rockably connected at its inner end to the vertical leg, a track boom extension pivotally connected to the outer end of the main boom, a carriage slidably mounted in said track boom extension, a load carrier secured to said carriage, a cylinder pivotally secured to the horizontal leg of the support, a piston slidably mounted in the cylinder, a piston rod secured to the piston extending exteriorly of the cylinder and pivotally connected to said main boom forwardly of the vertical leg, means on said load carrier for controlling the flow of fluid to and from the cylinder, an upright bracket rigidly secured to the inner end of the track boom extension, an auxiliary boom pivotally connected with the upper end of the upstanding bracket and to the vertical leg, means for varying the position of the main boom and the auxiliary boom on the vertical leg of the support, and means for varying the position of the cylinder and piston relative to the horizontal leg and the main boom.

9. A crane comprising a support, a main boom pivotally mounted at its inner end on said support for swinging movement in a vertical plane to a raised and a lowered position, means for swinging the boom on the support to raised and lowered positions, a track boom extension pivotally connected to the outer end of the main boom, a load carrier movable longitudinally on the track boom extension, and means including an auxiliary boom operatively connected to the support and to the track boom extension for maintaining said track boom extension in a horizontal plane at all times during the raising and lowering movement of the main boom.

10. A crane comprising a support including a platform, means rotatably mounting the support for swinging movement in a horizontal plane, an upright guide carried by the platform, a main boom slidably mounted in said guide, a track boom extension pivotally connected to the outer end of the main boom, a load carrier slidably mounted in said track boom extension, an upright frame secured to said track boom extension, an auxiliary boom pivotally connected to the upper end of said upright frame, a toggle lever connection between the platform and the inner end of said auxiliary boom, a link pivotally connecting the inner end of the auxiliary boom to the upright guide, a cylinder rigidly connected to and depending from said platform, a piston slidably mounted in the cylinder, a piston rod connected to the piston and pivotally connected to the main boom, the inner end of said main boom being pivotally connected to the toggle, and means on said load carrier for controlling the flow of fluid to and from the cylinder.
